CLAIM

The ornamental design for an indexed pallet, as shown and described.

DESCRIPTION

FIG. 1 shows a perspective view of a indexed pallet according to the principles of the present invention;

FIG. 2 is a top plan view of the pallet shown in FIG. 1, a rear elevational view not being shown as it is a mirror image of the front elevational view;

FIG. 3 is a right side elevational view of the pallet shown in FIG. 1, a left side elevational view not being shown as it is a mirror image of the right side elevational view;

FIG. 4 is a front elevational view of the pallet shown in FIG. 1; and,

FIG. 5 is a bottom plan view of the pallet shown in FIG. 1.
